UNITED STATES PATENT OFFICE.

ALEXANDER T. KASLEY, OF ESSINGTON, PENNSYLVANIA, ASSIGNOR TO WESTINGHOUSE ELECTRIC AND MANUFACTURING COMPANY, A CORPORATION OF PENNSYLVANIA.

GOVERNOR.

Application filed January 3, 1923. Serial No. 610,514.

To all whom it may concern:

Be known that I, ALEXANDER T. KASLEY, a citizen of the United States, and a resident of Essington, in the county of Delaware and 5 State of Pennsylvania, have invented a new and useful Improvement in Governors, of which the following is a specification.

My invention relates to governing mechanism, more particularly of the fluid pressure 10 type, and it has for its object to provide apparatus of the character designated which shall be economical to build and to operate, which shall be reliable and stable in operation, and which shall be capable of maintaining 15 closely regulated speeds for different loads imposed upon a machine with which the governing mechanism is associated.

Another object of my invention is to provide 20 fluid-pressure actuated governor mechanism which shall be capable of interrupting the supply of energy to a machine should the supply of pressure fluid to the governing mechanism fail or should parts of the governing apparatus break.

25 A further object of my invention is to provide a fluid-pressure governing mechanism whose exhaust is utilized for the purpose of lubricating any suitable parts or bearings.

Apparatus made in accordance with my 30 invention is illustrated in the accompanying drawings, forming a part of this application, in which Fig. 1 is a side elevation of a turbine showing my improved governing apparatus applied thereto; Fig. 2 is a diagrammatic and sectional view of the governing 35 apparatus shown in Fig. 1; Fig. 3 is a sectional detail view on a larger scale of a constant-pressure valve shown in Figs. 1 and 2; Fig. 4 is a detail view showing how the housing 40 for the speed-responsive mechanism is supported; and Fig. 5 is a diagrammatic view of distant-control mechanism.

Referring now to the accompanying drawings for an understanding of my invention, 45 I show a motor or prime mover, at 10, for example, a steam turbine, having an energy-controlling device or admission valve, at 11, the valve being moved in opening and closing directions in accordance with the load

by means of fluid-pressure governing mechanism which is operated by the shaft 12 of the prime mover.

The fluid-pressure governing mechanism comprises a pump 13 which delivers fluid under pressure to a motor device, at 14, the latter being connected to the energy-controlling device or admission valve, at 11, and a speed-responsive, pressure-relieving mechanism, at 15, being provided in order to secure operation of the apparatus in a manner to be described.

The pump 13 may be of any suitable type and it is driven by means of a shaft 16 which is geared to the prime-mover shaft 12 by means of any suitable gearing, at 17. See Fig. 4. The pump receives fluid from the storage reservoir 18 and delivers it under pressure through the passageway 19 to the motor device, at 14. In order that the pressure of fluid delivered to the motor device, at 14, may be constant, a pressure-regulating valve 20 is associated with a passageway 21, communicating with the passageway 19, as may be seen from Fig. 3, the pressure-regulating valve 20 serving to limit the maximum attainable pressure of fluid in the passageway 19. Therefore, the pump is capable of delivering fluid at a substantially constant pressure even though the speed of the pump may vary.

The motor device, at 14, comprises an operating cylinder or chamber 23 containing an operating piston, element, or abutment 24, connected to the rod 25, the latter being pivotally connected to a lever 26, fulcrumed at 27 and connected to the valve actuating stem or link 28. The piston, element, or abutment 24 is actuated in one direction, downwardly as illustrated, by fluid pressure, and it is actuated in the other direction by a spring or biasing means 29. Preferably, the spring or biasing means 29 serves to impart closing movement to the valve 11 so that, should the pressure of fluid fail, closure of the valve 11 is assured. The motor device includes suitable valve mechanism for controlling the admission and exhaust of fluid to the cylinder or chamber 23, whereby

the piston, element, or abutment 24 may be actuated.

The valve mechanism for the operating cylinder comprises a valve chamber 30, arranged in the head 31 for the operating cylinder 23. The head 31 is provided with a chamber or passage 32, which communicates with the pressure-supply passageway 19 and with the valve chamber 30. An exhaust passage or chamber 33 is provided in the head 31 and it communicates with the valve chamber 30. A supply passage 34 communicates with the operating cylinder 23 and it is provided with a portion 35 which communicates with the valve chamber, the latter portion communicating with the valve chamber 30 between the connections of the pressure-supply and exhaust chamber or passages 32 and 33 therewith.

20 A valve 36, preferably of the piston type, fits in the valve chamber 30 and it is provided with a piston valve portion 37 whose length is substantially equal to that of the passage 35. The piston valve is provided

25 with reduced portions 38 and 39, above and below the piston portion 37. As the piston portion 37 has an edge fit with the sides of the passage 35, when the valve is in its neutral position, it will be apparent that movement of the valve upwardly from this position places the pressure-supply passage or chamber 32 in communication with the operating cylinder 23 and that downward movement of the valve places the exhaust

30 chamber or passage 33 in communication with the operating cylinder. The piston valve 36 is preferably arranged coaxial with respect to the rod 25 and it has a close clearance 41 with respect thereto for a purpose

35 to be described.

When the piston valve 36 moves upwardly in response to an increase in load on the prime mover, the pressure-supply passage or chamber 32 is placed in communication with the operating cylinder 23, whereupon the operating piston 24 is moved downwardly to open the valve 11 wider to admit an increased quantity of motive fluid to the prime mover in order to take care of the increased load. This downward movement of the operating piston 24 is accomplished by a compression of the spring 29, whose effect will be more fully hereinafter set forth. With a decrease of load on the prime mover

50 the piston valve 36 moves downwardly to place the operating cylinder in communication with the exhaust by way of the passages 34 and 35, the reduced portion 38, and the exhaust chamber or passage 33.

60 The operating mechanism for the piston valve 36 to secure the upward and downward movements thereof referred to comprises a piston, element, or abutment 42 connected to the piston valve 36 and arranged

65 within a cylinder or chamber 43. The pis-

ton has a stem 44 on the opposite side from the piston valve and the piston and stem structure have a close sliding fit with respect to the rod 25. As shown, the stem 44 extends through the head 45 of the cylinder 43 and it abuts the lower end of the spring 29, the latter being normally held under compression between the stem and an abutment 46, such as a nut, on the rod 25.

70 The clearance space 41 (shown in an exaggerated manner in Fig. 2 for purposes of clearness) between the rod 25 and the interior of the piston valve 30 constitutes an orifice connection for the space of the cylinder 43 beneath the piston 42, this orifice connection including ports 47, which afford communication with the pressure-supply passage or chamber 32, and communication with the space beneath the piston 42 is afforded by means of ports 48. the piston 24 continues until the tension of the spring 29 is substantially equal to the effective fluid-pressure force acting beneath the piston 42 and the piston face 49 at which time the piston valve 36 occupies a neutral or cut-off position.

With an increase in speed of the prime mover, incident to a decrease in load, pressure beneath the piston 42 is relieved, with the result that the piston is forced downwardly by the spring 29, thereby connecting the operating cylinder 23 with the exhaust chamber or passage 33 by way of the passages 34 and 35 and the reduced portion 38 of the piston valve, whereupon the spring 29 is then effective to move the operating piston 24 upwardly. This upward movement of the operating piston 24 and its rod 25 results in movement of the valve 11 in a closing direction. The upward movement of the operating piston 24 is accompanied by a diminution in the force or compression of the spring 29; and, when the compression of the spring 29 is reduced so that the force thereof is substantially equal to the force of the fluid pressure effective beneath the piston 42, then the latter moves to equilibrium position with the piston valve 36 in a neutral or cut-off position.

It will, therefore, be seen that any change in load upon the prime mover is accompanied by a disturbance of the condition of equilibrium of the forces acting on the piston valve structure, with the result that the operating piston 24 is moved to secure movement of the admission valve 11 in the proper direction, this movement of the operating piston continuing until equilibrium of forces acting thereon is restored at which time the piston valve 36 occupies a neutral or cut-off position.

The speed responsive relief or bleeder apparatus comprises a hollow shaft 51, which is secured to the upper end of the pump shaft 16, and which communicates with the passageway 50 by means of ports 52, communicating with an annular chamber 53, the latter being connected to the passageway 50. The hollow shaft carries a suitable head 54 at its upper end, this head being provided with a bottom 55 and a partition 56 spaced above the bottom, the partition defining, with the bottom, an exhaust receiving chamber 57. The partition 56 and the bottom 55 are provided with openings to receive the valve cylinder 58 which is axially aligned with the hollow passage 59 of the shaft 51. The cylinder 58 is provided with ports 60 which are covered and uncovered in operation by means of a piston 61.

The piston 61 is connected to an arm 62 of a bell crank lever 63, the other arm 64 of the latter carrying a suitable weight 65, the centrifugal effect of which operates to

move the piston 61 upwardly to open the ports 60. A spring 66 is connected to the arm 64 and to the head 54 and its force opposes the centrifugal effect of the weight 65 and it tends to move the piston 61 downwardly to close the ports 60. In addition to the opposing forces just mentioned, acting on the piston valve 61, the force of the fluid beneath the piston 61 is also effective in determining the position thereof. In operation, whenever the piston 61 occupies a given position, the force of the fluid effective beneath the piston 61 added to the centrifugal force effective on the weight 65 equals the force of the spring 66.

The connection of the spring 66 with the arm 64 is of the adjustable type so that the tension of the spring 66 may be varied for the purpose of changing the normal speed of the prime mover. As shown, this adjustable connection consists of a threaded anchor member 67 for one end of the spring 66 which has threaded engagement with a screw 68 carried by the arm 64. The tension of the spring 66 may be varied merely by turning the screw 68 in one direction or the other.

The exhaust chamber 57 communicates with a collection chamber 69 by means of ports 70. The collection chamber is formed by a part of the stationary structure which includes the chamber 53; and, beyond the collection chamber 69, such stationary structure extends outwardly as indicated at 71 to constitute the bottom of the housing 72 for the rotary head 54. A drain 71' is shown in the bottom structure 71. The exhaust passage or chamber 33 in the head 31 is connected to an exhaust passageway 73 which leads to bearings indicated at 74 requiring lubrication. If desired, the space beneath the piston 24 may be connected to the passageway 73 by means of a suitable passageway 75. Also, if desired, the passageway leading from the constant pressure valve 20 preferably communicates with the passageway 73 leading to the bearings. Likewise the discharge conduit 102 for the chamber 69 may be connected to the bearing line or header. The bearings 74 as well as the collection chamber 69 discharge surplus oil into suitable passageways by which it is returned to the oil receiver 18.

The apparatus just described operates as follows:

The prime mover 10 drives the pump 13 which supplies fluid under pressure to the passageway 19 communicating with the fluid pressure passage or chamber 32 of the operating cylinder head 31, such pressure being maintained substantially constant due to the employment of a constant pressure valve 20. Fluid under pressure flows from the pressure chamber or passage 32 to the space in the cylinder 43 beneath the piston

42 by way of the orifice connection constituted by the hole 47 clearance space 41 between the piston valve 36 and the rod 25.

The spring 29 under initial compression 5 between the stem 44 of the piston 42 and the nut 46 on the rod 25 serves to exert its force on the pistons in directions opposite to the fluid pressure forces exerted thereon. Also, the force of the spring 29 is exerted on 10 the rod 25 in such a direction as to impart movement in a closing direction to the valve 11.

For normal operation of the prime mover at a given load, the piston valve 36 occupies 15 a neutral or cut-off position, the piston 42 being maintained in an equilibrium position, the force of the spring 29 thereon being balanced by the fluid pressure force effective beneath the piston 42 and beneath 20 the face 49.

Since fluid is being supplied to the space beneath the piston through the orifice connection, it is necessary, for a given speed, that fluid shall be bled from the cylinder 43 25 beneath the piston 42. Therefore, for all speeds, there is more or less bleeding of fluid through the passageway 50, the passageway 59, and the ports 60, the restriction of the latter being under the control of the piston 30 valve 61.

For a given speed and load, the piston 42 is maintained in equilibrium position by an oil pressure acting therebelow, which, in turn, is maintained substantially constant 35 by the valve 61 cooperating with the ports 60, that is, the valve 61 occupies a given position which depends upon the force of the oil pressure acting beneath the piston 61, upon the centrifugal force effective on the 40 weight 65 and upon the tension of the spring 66.

If the load on the prime mover should increase, the speed thereof would drop slightly with the result that the centrifugal force of 45 the weight member 65 would decrease, thereby disturbing the equilibrium condition of the forces acting on the piston 61 and permitting the spring to move the piston 61 downward to restrict the passages or ports 50 60.

The restriction of bleeding from the cylinder 43 results in the building up of pressure beneath the piston 42 and, the fluid pressure exceeding the force of the spring 55 29, the piston 42 moves upwardly to establish communication between the pressure supply chamber or passage 32 and the operating cylinder 23 so that fluid under pressure may act on the piston 24 to move the 60 admission valve in an opening direction to supply an increased quantity of motive fluid to the prime mover to meet the increased load.

Whenever there is a decrease in load, resulting in a decrease in fluid pressure be-

neth the piston 42, the piston valve moves downwardly to connect the operating cylinder with the exhaust, whereupon the spring 29 is effective to pull the piston 24 upwardly to move the admission valve 11 in a closing direction to restrict the flow of motive fluid to the prime mover. This upward movement of the operating piston continues until the force of the spring 29 is diminished sufficiently so that the piston 42 can return to 75 neutral position.

If the pressure of fluid for the governing mechanism should fail, the pressure of the spring 29 would immediately exceed the pressure of fluid beneath the piston 42, 80 whereupon the latter would move downwardly to place the operating cylinder 23 in communication with the exhaust chamber or passage 33, with the result that the operating piston 24 and the rod 25 would move 85 upwardly and the admission valve 11 would move in a closing direction due to the force of the spring 29. If the spring 66 of the speed-responsive device should fail, then the piston valve 61 would be free to move to expose to a greater extent the ports 60 under the influence of the weight 65 and the pressure of fluid effective beneath the piston valve 61. The sudden reduction of fluid pressure beneath the piston 42 in this way 90 results in the downward movement of the latter and the movement of the admission valve in a closing direction under the influence of the spring 29 in the manner just 95 staged.

In operation there is more or less leakage of fluid by the piston 42; and, if the discharge of fluid from the cylinder 43 above the piston 42 is impeded, a back pressure is imposed upon the other side of the piston whose effect assists the spring 29, with the result that a higher oil pressure is necessary beneath the piston 42 in order that the latter may acquire an equilibrium position. The greater the back pressure the less the 100 speed of the prime mover for the reason that it is necessary that the piston valve 61 restrict the bleeding of fluid from beneath the piston 43 to an extent sufficient to obtain an equilibrium condition of this piston. Accordingly, therefore, I show a pressure regulating valve associated with the head 45 for regulating the back pressure in the cylinder 43 and above the piston 42.

The pressure-regulating valve comprises a valve member 76 which cooperates with a seat provided at one end of the outlet passage 77. A spring 78 abuts against one end of the valve member and the other end of the spring abuts against an adjustable member 79, which may be adjusted for the purpose of varying the compression of the spring 78, whereby the pressure of fluid necessary to raise the valve member 76 may be varied. Fluid which has passed the 110 120 125 130

valve member preferably enters a chamber 80 which communicates with a suitable drain 81.

If the compression of the spring 78 is lessened, the speed of the prime mover tends to increase for the reason that the back pressure above the piston 42 is less and consequently the fluid pressure beneath the piston 42 to hold the latter in neutral or equilibrium position is less, the diminished pressure beneath the piston 42 being obtained by a slightly greater opening of the ports 60 which takes place due to upward movement of the piston valve 61 incident to an increase 15 in speed of the turbine.

The first effect of decreasing the back pressure on the piston 42 is for the latter to move upwardly so as to supply fluid under pressure to the operating piston 24 to move 20 the latter downwardly and to open wider the admission valve 11, whereby more motive fluid is admitted to the prime mover to secure the increase in speed already referred to for the purpose of bleeding the pressure 25 beneath the piston 42 in order that the latter may attain a position of equilibrium.

An increase in compression of the spring 78, results in a diminution in the speed of the prime mover for the reason that as soon 30 as the back pressure is increased in this way, the piston 43 moves downwardly to place the operating cylinder 23 in communication with the exhaust, whereupon the spring 29 is effective to move the operating piston 24 35 and rod 25 upwardly to move the admission valve 11 in a closing direction, this movement continuing until the fluid pressure effective beneath the piston 42 is equal to the opposed back pressure and the pressure of 40 the spring 29. As soon as the flow of motive fluid to the prime mover is restricted, its speed drops, with the result that the centrifugal force of the weight member 65 declines and the spring member 66 contracts 45 until the speed-responsive device attains a condition of equilibrium. This operation of the speed-responsive device results in the restriction of bleeding from beneath the piston 42, whereby the fluid pressure beneath this piston builds up.

It will, therefore, be seen that an equilibrium or neutral position of the piston 42 is attained, when the back pressure is increased, both by a decrease in the compression 55 of the spring 29 and by an increase in the fluid pressure beneath the piston 42 incident to a restriction in the bleeding; and, when the back pressure is decreased, the piston 42 attains a position of equilibrium both 60 by a decrease in the compression of the spring 29 and a decrease in the pressure beneath the piston 42, the latter decreased pressure being obtained by an increased capacity for bleeding incident to an increase 65 in speed of the prime mover.

The operation of speed changing just referred to is particularly advantageous when synchronizing one machine with another. This operation may be conveniently carried out from a distance, as will be apparent 70 from Fig. 5. In this view, I show a lever 82 arranged between the screw 79 and the spring 78, the lever being fulcrumed at 83 and having its other end pivotally connected at 84 with a rod or link 85, which is connected to the diaphragm of a pressure device 86. One side of the diaphragm is subject to atmospheric pressure while the other side is subject to a sub-atmospheric pressure, which may be varied, whereby the 80 compression of the spring 78 may be varied at will.

The sub-atmospheric side of the regulating device 86 is connected by means of a passageway 87 with the throat of an ejector 85 or aspirator 88, the latter preferably utilizing water at constant pressure which is discharged axially of the ejector or aspirator by means of a suitable passageway 89. If water is used as the motive fluid of the 90 ejector or aspirator, this water may be conveniently supplied from the turbine gland supply. In order that the pressure device 86 may have the sub-atmospheric pressure varied, I provide means for bleeding air 95 from the atmosphere into the passageway 87.

The air bleeding arrangement preferably comprises valve mechanism at 90 which may be supported by a switch board 91 of a power plant. The valve mechanism controls the admission of air from the atmosphere through the passageway 92 to the passageway 87. This valve mechanism preferably comprises a suction operated valve member 93 which is biased toward its seat by means of a spring 94 connected to the valve and to a tension adjusting member 95. As shown, the tension adjusting member 95 is a simple lever fulcrumed at 96 and having a clamping adjustment 97 with respect to a sector 98. As the tension of the spring 94 is increased bleeding of the passageway 87 is diminished with the result that the sub-atmospheric pressure is increased and the tension of the spring 78 is diminished. If 110 the tension of the spring 94 is diminished, the sub-atmospheric pressure in the passageway 87 is increased with the result that the rod 85 moves upwardly and the tension of the spring 78 is increased. It will, therefore, be apparent that, with the apparatus shown in Fig. 5, the tension of the back pressure spring may be readily controlled 115 from a distance.

A closer degree of regulation may be obtained by the use of a spring 29 of finer scale; however, as this spring is weakened, the stability of the mechanism is decreased. With a stronger spring, the percentage in 125 speed variation from no load to full load 130

may be greater, but the stability of the mechanism is also increased.

The speed of the turbine may be varied considerably by changing the tension of the 5 spring 66 of the speed-responsive mechanism. A change in tension of this spring means that both centrifugal forces of the weight member 65 and the oil pressure effective beneath the piston 61 must be changed 10 in order that the speed-responsive mechanism may attain a condition of equilibrium. For example, if the tension of the spring 66 is increased, this means that the piston valve member 61 is moved inwardly to restrict the ports 60 which, as already stated, results in the building up of pressure beneath the piston 42 and the consequent opening of the admission valve 11 to a wider position. This results in an increase in the 15 speed of the prime mover or turbine, and the speed-responsive mechanism attains a condition of equilibrium where the spring 66 and the centrifugal force of the weight member 65 and the effect of the oil pressure 20 on the piston 61 are balanced, with a greater restriction of the ports 60. An increase in tension of the spring 66, therefore, results in a higher speed for the prime mover. A decrease in tension of this spring results in 25 a contrary effect.

My improved governing mechanism preferably uses lubricating oil as an actuating fluid. I, therefore, show the outlet passageway 73 for the discharge chamber 33, the 30 outlet passageway 75 for the space beneath the operating piston 24, the discharge conduit 103 for the discharge chamber 69, and the pressure-relief valve 20 for the pressure-supply conduit 19, all communicating with 35 the conduit 100, which is provided with connections 101 leading to the bearings 74 for the purpose of lubricating the latter. Surplus oil from the bearings is discharged into a passageway or conduit 102, which communicates with the receiver or reservoir 18. 40 It will, therefore, be seen that I have provided a combined governing and lubricating system in which oil is supplied at sufficient pressure from parts of the governing mechanism to secure adequate lubrication.

When starting up the prime mover, it is necessary to supply fluid to the passageway 19 from some auxiliary source. Accordingly, I show, a passageway 105 adapted to be connected to any suitable source of fluid under pressure and which is controlled by means of a valve 106. In starting, fluid under pressure from the auxiliary source is admitted to the passageway 19, whereupon 50 such fluid enters the pressure chamber or passage 32 and then passes through the restricted orifice connection 41, moving the piston 42 upwardly so that such fluid under pressure may be supplied to the operating piston 24 in order to move the latter down-

wardly for the purpose of opening the admission valve 11. The prime mover then starts, and thereafter the auxiliary source of fluid under pressure may be cut off and the pressure developed by the pump 13 solely 70 relied upon.

It will be obvious to those skilled in that art that the fluid-pressure operated mechanism for the prime mover valve as well as the fluid-pressure controlling mechanism for the operated mechanism may be of any suitable type, or design, although the preferable type is the cylinder and piston kind. Also, while a spring is shown for closing the admission valve, it is to be understood that 75 any device capable of producing the same result may be used.

While I have shown my invention in but two forms, it will be obvious to those skilled in the art that it is not so limited, but is 80 susceptible of various other changes and modifications without departing from the spirit thereof, and I desire, therefore, that only such limitations shall be placed thereupon as are imposed by the prior art or as 85 are specifically set forth in the appended claims.

What I claim is:

1. The combination with a prime mover having an admission valve, of governing mechanism for controlling the speed of the prime mover comprising a movable pressure-actuated element connected to the valve, a source of fluid under pressure, a valve for controlling the admission and exhaust of fluid to one side of said element, a pressure-actuated element connected to the valve, a restricted orifice connection for supplying fluid to one side of the latter element from said source, means for relieving the fluid pressure on the latter element, and biasing means to secure movements of the elements in directions opposite to movements thereof in response to fluid pressure whenever the force of the biasing means exceeds that of the fluid pressure.

2. In governing mechanism for controlling the supply of energy to a machine, the combination of energy-controlling mechanism including an element movable by fluid under pressure, a source of fluid under pressure, means for supplying fluid to said element from said source and for exhausting fluid from said element, a movable element connected to the last-named means, means for supplying fluid at a lower average pressure to one side of the last-named element, biasing means cooperating with said last-named element to oppose movement thereof in response to fluid pressure, and means for relieving the pressure of fluid applied to said last-named element.

3. In governing mechanism for controlling the supply of energy to a machine, the combination of energy-controlling mecha-

nism including an element movable by fluid under pressure in one direction, spring means for moving said mechanism in the other direction, a source of fluid under pressure, means for supplying fluid to said element from said source and for exhausting fluid from said element, a movable element connected to the last-named means, means for supplying fluid from said source at a lower average pressure to one side of the last-named element, biasing means cooperating with said last-named means and said element to oppose the fluid pressures, and means for relieving the pressure of fluid applied to said last-named element.

4. In governing mechanism for controlling the supply of energy to a machine, the combination of energy-controlling mechanism including an element movable in one direction by a fluid under pressure, a source of fluid under pressure, means for supplying fluid to said element from said source and for exhausting fluid from said element, a movable element connected to the last-named means, an orifice connection for supplying fluid from said source to one side of the last-named element, spring means cooperating with said moving elements and exerting its force thereupon in opposition to the fluid pressures applied thereto, and means for relieving the pressure of fluid applied to said last-named movable element in accordance with the speed of the machine.

5. The combination with a steam motor having an admission valve, of governing mechanism for the motor comprising a movable abutment connected to the valve, a source of fluid under pressure, a valve for controlling the admission of fluid from said source to one side of the abutment and the exhaust of such fluid therefrom, an abutment connected to the valve, a restricted orifice connection for supplying fluid to one side of the latter abutment from said source, speed-responsive means for relieving the fluid pressure on the latter abutment, and biasing means to secure movements of the abutments in directions opposite to movements thereof in response to fluid pressure whenever the force of the biasing means exceeds that of the fluid pressure.

6. The combination with a motor having an admission valve, of governing mechanism for the motor comprising a movable abutment connected to the valve, a source of fluid under pressure, a valve for controlling the admission of fluid from said source to the abutment and for controlling the exhaust of fluid therefrom, a movable abutment carried by the valve and normally subject to a pressure less than that of said source, speed-responsive means for relieving the pressure applied to the latter abutment, and spring means operative when the pressure on the latter abutment is relieved to move the valve

to exhaust fluid from the first abutment and then to move the admission valve toward its closing position.

7. The combination with a motor having an admission valve, of governing mechanism for the motor comprising a spring for moving the valve in a closing direction, an operating piston for moving the valve in an opening direction and in opposition to the spring, a source of fluid under pressure, a piston valve for controlling the admission of fluid from said source to one side of said piston and the exhaust of fluid therefrom, an operating piston connected to the piston valve and subject to the pressure of said spring on one side and to the pressure of fluid on the other side, and speed-responsive means for relieving the pressure of fluid applied to the latter operating piston.

8. The combination with a motor having an admission valve, of a governing mechanism for the motor comprising an operating piston, a rod for connecting the piston to the admission valve, a source of fluid under pressure, a valve for controlling the admission of such fluid to one side of the piston and the exhaust thereof therefrom, an operating piston for the valve, a spring under compression arranged between the operating piston of the valve and said rod, means for admitting fluid under pressure to the valve-operating piston to oppose the spring, and speed-responsive means for controlling the relief of fluid pressure from said valve-operating piston so that the valve may come to a neutral position under influence of the spring.

9. The combination with a motor having an admission valve, means for developing fluid under pressure driven by said motor, an operating piston connected to the admission valve, a valve for controlling the admission of fluid from said pressure-developing means to one side of said operating piston and the exhaust of fluid therefrom, an operating piston connected to the valve, means for supplying fluid under pressure to one side of the latter operating piston, a spring for exerting forces on said operating pistons in opposition to the fluid pressure forces applied thereto, and speed-responsive means for relieving the pressure of fluid applied to the operating piston of the valve.

10. The combination with a motor having an admission valve, of governing mechanism for the motor comprising pressure-developing means driven by said motor, an operating cylinder, an operating piston in the cylinder, a rod for connecting the piston to the admission valve, a piston valve for controlling the admission of fluid from said pressure-developing means to said piston and the exhaust of fluid therefrom, a second operating cylinder in axial alignment with

the first cylinder, an operating piston in the second cylinder and connected to the piston valve, means for supplying fluid to the second operating piston at a pressure normally less than that of said pressure-developing means, a spring under compression arranged between said rod and the second operating piston and exerting its force on the latter in opposition to fluid pressure, and speed-responsive means for relieving pressure from the second operating piston.

11. The combination with a motor having an admission valve, of governing mechanism therefor comprising fluid pressure-developing means driven by the motor, an operating cylinder, an operating piston arranged within the cylinder, a rod for connecting the operating piston to the admission valve, a piston valve arranged coaxial with said rod for controlling the admission of fluid from said pressure-developing means to one end of the operating cylinder and the exhaust of fluid therefrom, a second operating cylinder aligned with the first cylinder, a second operating piston arranged within the second operating cylinder and connected to the piston valve, means for admitting fluid under pressure to one side of the second operating piston through a restricted orifice connection, a spring under compression arranged between said rod and the second operating piston and serving to oppose the fluid pressures applied to the pistons, and speed-responsive means for relieving the fluid pressure applied to the second operating piston.

12. The combination with a motor having an admission valve, of governing mechanism for the motor comprising fluid-pressure developing means driven thereby, an operating cylinder, an operating piston arranged within the cylinder and connected to the admission valve, a valve for controlling the admission of fluid from said pressure-developing means to one end of the operating cylinder and the exhaust of fluid therefrom, a second operating cylinder, a second operating piston arranged within the cylinder and connected to the valve, a restricted orifice connection between the pressure-developing means and the second operating cylinder, a spring under compression for exerting its force against said operating pistons in opposition to the fluid pressures applied thereto, and speed-responsive means for relieving the pressure of fluid applied to the second operating piston.

13. The combination with a motor having an admission valve, of governing mechanism for the motor comprising pressure-developing means driven by the motor, an operating cylinder, an operating piston arranged within the cylinder, a rod for connecting the piston to the admission valve, a slide valve for controlling the admission of

fluid from said fluid-pressure developing means to one end of the cylinder and the exhaust of fluid therefrom, a second operating cylinder, a second operating piston in the second operating cylinder and connected to the slide valve, a restricted orifice in the slide valve for supplying fluid from said pressure-developing means to one side of the second operating piston, a spring under compression between the first and second operating pistons for normally opposing the fluid pressures applied thereto, and speed-responsive means for delivering the pressure of fluid applied to the second operating piston.

14. The combination with a motor having an admission valve, of governing mechanism for the motor comprising fluid-pressure developing means driven by the motor, an operating cylinder, an operating piston within the cylinder, a piston rod for connecting the piston with the admission valve, a piston valve surrounding the piston rod and having slight clearance with respect thereto, a valve cylinder having passages communicating with said pressure-developing means and with the exhaust, means on the valve for placing the operating cylinder in communication with the pressure-developing means or with the exhaust dependent upon the valve position, a second operating piston connected to the valve, ports in the valve connecting the clearance space with respect to the piston rod with said pressure-developing means and with the space at one side of the second operating piston, a spring under compression and acting on both pistons to oppose the fluid pressures applied thereto, and speed-responsive means for relieving the pressure of fluid applied to the second operating piston.

15. The combination with a prime mover having an admission valve, of a spring for moving the valve in a closing direction, an operating piston for moving the valve in an opening direction, fluid-pressure developing means driven by the prime mover, a valve for controlling the admission of fluid under pressure from said pressure-developing means to one side of the piston and the exhaust of fluid therefrom, an operating piston connected to the valve, a restricted orifice connection between the pressure-developing means and one side of the second operating piston, adjustable pressure-relief means associated with the space at the other side of the second operating piston, and speed-responsive means for relieving the pressure of fluid applied to the first side of said second operating piston.

16. The combination with a prime mover having an admission valve, of a spring for moving the valve in a closing direction, a fluid-motor device for moving the valve in an opening direction and in opposition to

the spring, a hollow shaft driven by the prime mover, a valve for one end of the shaft, speed-responsive means for controlling the opening and closure of said valve and rotating with the hollow shaft, and an exhaust connection between the motor device and the hollow shaft, whereby upon over-speeds of the prime mover, the rate of ex-

haust of fluid from the fluid motor is increased thereby permitting movement of the admission valve in a closing direction due to the spring.

In testimony whereof, I have hereunto subscribed my name this 28th day of December, 1922.

ALEXANDER T. KASLEY.
